DOOR CONTROLLING SYSTEM AND APPARATUS

Wallace F. Moore, New Britain, Conn., assignor to The American Hardware Corporation, New Britain, Conn., a corporation of Connecticut

Application June 10, 1931, Serial No. 543,400

7 Claims. (Cl. 70—50)

My invention relates to systems and apparatus for controlling doors and has special reference to such systems and apparatus for closing and locking doors.

5 One of the objects of my invention is to provide a novel and improved system and apparatus of this character.

Another object of my invention is to provide means controllable from one or any desired number 10 of points for automatically closing and locking one or a plurality of doors.

Another object of my invention is to provide a novel and improved electrically controlled locking means for doors.

15 Still another object of the invention is to provide a novel and improved door closer.

The several features of my invention, whereby the above mentioned and other objects may be attained, will be readily understood from the 20 following description and accompanying drawings, in which:

Figure 1 is a side view, partly in section, of a door check which may form a part of my improved apparatus;

25 Fig. 2 is a plan view of the same;

Fig. 3 is a detail plan view of a magnetically operated device forming a component part of the check, the cover of the casing of the device being removed;

30 Fig. 4 is a sectional view taken on the line 4—4 of Fig. 3;

Fig. 5 is a sectional view taken on the line 5—5 of Fig. 4;

35 Fig. 6 is a detail perspective view of an armature and associated parts of said magnetically operated device;

Fig. 7 is a detail sectional view on the line 7—7 of Fig. 4;

40 Fig. 8 is a plan view of a keeper which may form a part of my improved apparatus, with the cover of the casing of the keeper removed;

Fig. 9 is a sectional view taken on the line 9—9 of Fig. 8, the keeper being shown in locked or closed position;

45 Fig. 10 is a similar view of the keeper shown in open position;

Fig. 11 is a sectional view taken on the line 11—11 of Fig. 8;

50 Fig. 12 is a detail sectional view taken on the line 9—9 of Fig. 8;

Fig. 13 is a sectional view of a portion of a door case showing my improved keeper applied thereto;

55 Fig. 14 is an edge view of a corresponding portion of the door;

Fig. 15 is a wiring diagram of my improved system; and

Fig. 16 is a wiring diagram which may be used with one or more keepers where no electrically controlled door-checks are employed.

5 My improved system and apparatus as illustrated in the drawings, is particularly adapted for use where it may be desirable in case of emergency to quickly close and lock one or more, or all of the doors of a room or building, from one 10 or more remote points. In the preferred embodiment of my invention, such closing and locking of the doors may be accomplished by closing an electric circuit by means of one or more push buttons conveniently located in the building or 15 elsewhere.

To accomplish the closing of the doors, a door-check is employed which is adapted to operate in the usual manner during normal opening and closing of the door, and which is provided with 20 means to hold the door open. Associated with each door-check is a magnetically operated device which upon being energized releases the holding means of the check so as to permit the spring-actuated door closing arm to close the door.

25 The locking means for the door comprises a keeper and a key-operable latch-bolt. The keeper is pivotally mounted to permit it to be swung into open and closed positions, but normally the keeper is in open position, thus allowing free opening 30 and closing of the door. A magnetically operated device is associated with each keeper whereby, upon closing an electric circuit, the keeper is moved to closed position, so that when the door is closed, the latch-bolt by engagement with the 35 keeper locks the door.

30 My improved door-check and closer as illustrated in Figs. 1 and 2 of the drawings is particularly adapted for use in connection with my improved system. The door-closer is shown applied to a door frame or door-case 2 and a door 4, the door being shown open. The door-closer comprises the usual casing 6 which is secured to the door-case. A spring-actuated door closing arm 8 is connected by a loop 10, a connecting rod 12, 45 and a bracket 14 to the door frame. The spring actuated arm 8 carries a double detent or pawl 16 for engagement with the teeth of a ratchet wheel 18 connected with the door closing spring in the usual manner.

50 A ring 20 is adjustably secured to the upper end of the case 6 and carries a plate 22 having a pocket 24. This pocket 24 is adapted to receive a downwardly spring-pressed detent 26 carried by the spring actuated arm 8, and when the detent 55

is received in its said pocket and its spring is under tension, it is adapted to hold the door open. This detent comprises a steel ball which is received in the lower end of a vertical aperture 28 in the spring actuated arm 8. The detent ball is 5 pressed downwardly when in said pocket, by means of a plunger 30 mounted in said aperture which in turn is actuated upon by a coiled spring 32 interposed between the upper end of the 10 plunger and a screw-plug 34. The downwardly spring-pressed plunger 30 is provided with a flange that engages a shoulder in the aperture 28 to limit the downward movement of the plunger, so that when the ball 26 rides out of its pocket 15 and as it leaves the end of the plate 22, it drops out of engagement with the lower end of the plunger and thus rotates freely during the completion of the closing of the door.

The door-closer is further provided with means 20 for releasing the tension of the detent spring 32 so as to render said spring and its associated detent plunger 30 inoperative to hold the detent ball 26 in said pocket, and thus permit the spring actuated arm 8 to close the door. This means 25 comprises a lever 36 mounted on the top side of the spring actuated arm 8. One end of this lever is provided with a recess 38 which loosely receives the upper end of a boss 40 on the arm 8, the aperture 28 extending through this boss. This recess 38 is provided with an aperture through which is screw-threaded the abutment plunger 34 for the detent spring 32. The lever 36 is 30 detachably fulcrumed on the arm 8 by means of an inwardly directed tongue or lug 42 thereon which 35 is received in a slot in the side of the boss 40. The outer end of the lever 36 is held down by means hereinafter described.

The top side of the door closing arm 8 is provided with a member 44 which has a recess 46 for 40 receiving the outer portion of the lever 36 when the device is in normal position. The under side of the lever 36 is provided with a shoulder 48 which engages the outer face of the member 44.

A post 50 is pivoted at its upper end in a recess 45 in the under side of the lever 36. This post extends downwardly through an elongated aperture in the arm 8 and its lower end is provided with laterally projecting shoulders, one of which is shown at 52. The sides of the post 40 are flattened and arranged closely adjacent the side walls 50 of the aperture through which it extends.

With this construction, upon releasing the outer end of the lever 36, the detent spring 32 acts immediately to throw said lever upwardly about the 55 axis of the fulcrum formed by the lug 42. Also, as the lateral shoulder 52 on the post 50 strikes the under side of the arm 8, the lever is forced forwardly a sufficient distance to disengage the fulcrumed lug 42 from the upper wall of the slot 60 in which it is received. Thus, upon the outer end of the lever 36 being released, the spring-actuated arm 16 is permitted immediately to close the door.

The door closing arm is provided with an opening 54 formed by means of an enlarged collar portion 55 on the arm beneath the forward end portion 65 of the lever 36.

Except as hereinabove described, the parts of the door check above referred to may be and preferably are the same as the corresponding parts of the door-check described and claimed in my pending application Serial No. 459,677, filed June 7, 1930.

In accordance with the present invention, the 75 lever 36 is held down by means of a trigger mem-

ber 56, the end of which engages an upwardly directed shoulder 58 on the outer end of the lever 36, the end portion of the lever extending downwardly through the aperture 54 in the spring-actuated arm. The trigger 56 is pivoted on a pin 60 (Figs. 3 to 6) having its ends secured in the side walls of a casing 62 that is secured by screws 64 to the collar portion 55 of the door closing arm 8. The trigger 56 is normally held in horizontal position by a tongue 66 on its inner end 10 engaging a shoulder 68 on a dogging member 70 pivoted on a pin 72. The dogging member 70 is adapted to be swung to release the trigger and thereby permit the lever 36 to swing upwardly, by means of a lost motion connecting member 74 15 carried by one end of an armature 76 which is mounted on the same pivot pin 72 with the dogging member 70, the member 74 being provided with a slot that receives the upper end of the dogging member. The armature 76 and dogging 20 member 70 are held in position so as to hold the shoulder 68 on the dog in holding engagement with the trigger 56 by means of a spring 78. The armature 76 is adapted to be drawn back to release the trigger 56 by means of a pair of electro- 25 magnets 80.

With this construction, it will be apparent that, upon closing the circuit connection with the electro-magnets, the lever 36 is immediately released, allowing the door closing arm to close the door. 30

As shown, means is provided whereby when the lever 36 is released, circuit connection with the electro-magnets is broken, and there is provision whereby the connection cannot be accidentally re-established. To provide for this, the lead wire 35 from one of the magnets is grounded on the spring-actuated arm 36. The other lead wire from the magnet is attached to the binding-post 81 which in turn is connected to one side of a power supply. The other binding-post 83 is connected to a spring 82 which is secured to a block 40 of insulating material 84 so as to be insulated from the spring-actuated arm. This contact spring 82 has a tongue extension which extends between upstanding lugs 86 formed on the block 45 84. These lugs receive between them the forward portion of the lever 36, so that when the lever is held down the underside of the arm is in electrical contact with the contact spring 82. When, however, the lever is released, it is disengaged from the contact spring so as to open the 50 circuit.

In order to insure against the circuit being accidentally closed by the lever 36 dropping, a flat spring 88 is secured to the side of the lever 55 36, the lower end of which abuts against the end of one of the lugs 86 on the block 84 so as to prevent the lever 36 from falling back into contact with the contact spring 82. Thus, after the device is operated, the electrical connection between the lever 36 and the contact spring 82 is broken, and it is necessary to re-set the device 60 before it can again be operated through the closing of the circuit connection with the electro-magnets. 65

The keeper which is indicated at 90 (Figs. 8 to 11) is mounted in a suitably formed casing 92 that is secured in the door case 2 (Fig. 13). This keeper is pivotally mounted on a pin 94, and is pressed toward holding or closed position as 70 shown in Figs. 8 and 9, by means of a spring 96 coiled about the pin 94. Normally, however, the keeper is held in effective or open position (Fig. 10) by the engagement of a latching lug 98 with a shoulder 100 on the rear side of the 75

keeper. This lug 98 is an extension of a member that connects a dogging member 102 with an armature 104, the armature and dogging member being pivotally mounted on the same pin 106. 5 The armature is adapted to be swung back by means of two electro-magnets 108, and is pressed in a direction away from the magnets by means of a spring 110. With this construction, when the magnets are 10 energized, the lug 98 is drawn out of engagement with the shoulder 100 on the keeper, allowing the spring 96 of the keeper to swing it into closed position. As the keeper reaches closed position, a pin 112 on the keeper engages a projection 114 on a trip lever 116 pivoted on a side 15 of the casing, and swings the rear end of the trip lever upwardly so that when the electro-magnets are deenergized and the armature and dogging member 102 swing away from the electro-magnets, a shoulder 118 on the member 102 is positioned beneath the rear end of the trip lever. The trip lever 116 by engagement with said shoulder 118 and the pin 112 securely holds the keeper in effective or closed position. In order 20 to release the keeper and return it to open position, an aperture 120 is provided therein through which a wire or other instrument may be inserted to retract the armature and the dogging member 118 from holding engagement with the 25 trip lever 116, thus allowing the keeper to be swung back and held by the lug 98 in open position.

In addition to the switching device in the door-check as above described for breaking the circuit when the system has operated to close and lock the doors, there may be provided an additional switching device associated with the keeper. This latter switching device is used where the keeper is employed without an electrically controlled door-check. To provide for this the lead wire from one of the magnets is grounded to the keeper casing 92. The other lead wire from the magnet is attached to binding post 124 which in turn is connected to one side 45 of the power supply. The other binding-post 126 is connected to a spring 128 (Fig. 11) said spring being insulated from the case. When the keeper is locked in open position, a contact is made between the keeper and spring 128. When the 50 keeper is swung into closed position it disengages from the spring 128, thus disconnecting the magnets from the power supply.

In Figs. 13 and 14, I have shown my improved electrically operated keeper in association with the bolt 132 of a conventional pin tumbler lock 134. Also, mounted in the door is the lock 136 equipped with knobs 138, the usual strike or keeper-plate 140 being mounted in the door case.

It will be apparent that when the electrically 60 operated keeper 90 is locked in open or ineffective position, the door may be opened and closed by the knobs and key of the conventional lock 136. As soon, however, as the keeper is moved to closed position upon closing the circuit, it coacts with the latch-bolt of the special lock 134, and as this lock is not equipped with knobs, the door can be opened only by use of a key.

Upon closing the circuit by means of any one of the push buttons 144, the electro-magnets 80 associated with the door-checks act to release the holding devices of the checks so as to allow their spring-actuated arms 8 to immediately close the several doors. Simultaneously with this operation, the electro-magnets 108 cause the keeper to be swung into closed position, so that as

the doors are closed the latch-bolts 132 latch into position behind the keepers. As the holding levers 36 of the door-checks are released, the switching devices comprising said levers and the springs 82 immediately open the circuit.

In Fig. 15 the system is shown without the use of the electrically operated door-checks. In such case, switching devices comprising the springs 128 are associated with the keepers so that when the keepers are moved into closed positions, the 10 circuit is opened.

As will be evident to those skilled in the art, my invention permits various modifications without departing from the spirit thereof or the scope of the appended claims. 15

What I claim is:

1. The combination of a door, a door case, a latch-bolt mounted in one of said members, a keeper for the latch-bolt mounted in the other member and adapted to be moved into opened 20 and closed positions, a latching device acting automatically to latch and retain the keeper in opened position when the keeper is moved into said position, means for moving the keeper into closed position upon releasing said latching device, and controllable electrically operated means for releasing said retaining means and for holding said keeper in closed position. 25

2. The combination of a door, a door case, a latch-bolt mounted in one of said members, a keeper for the latch-bolt pivotally mounted in the other member so as to permit it to be swung into opened and closed positions, a spring tending to swing the keeper into closed position, a latching device for normally retaining the keeper 30 in open position against the tension of said spring, and controllable electrically operated means for releasing said retaining device for the keeper to permit the keeper to be moved by its spring into closed position, and for holding the keeper in 35 closed position said latching device acting automatically to latch and retain the keeper in opened 40 position when the keeper is moved into said position.

3. The combination of a door, a door case, a latch-bolt mounted in one of said members, a keeper for the latch-bolt mounted in the other member and adapted to be moved into opened and closed positions, a device for retaining the keeper open, means for moving the keeper into closed 45 position upon releasing said retaining device, and controllable means comprising an electric circuit acting upon closing the circuit to release said holding means, and comprising means acting automatically to open the circuit upon the keeper 50 being moved into closed position. 55

4. The combination of a door, a door case, a latch-bolt mounted in one of said members, a keeper for the latch-bolt mounted in the other member and adapted to be moved into opened 60 and closed positions, a device for retaining the keeper in open position, means for moving the keeper into closed position upon releasing said retaining device, and controllable means comprising an electric circuit acting upon closing the circuit to release said holding means, and a switching device acting automatically to open the circuit upon the keeper being moved into closed 65 position.

5. In a door closer, the combination of a spring-actuated door closing arm, a stop member, a detent carried by said arm and adapted to engage said stop member when the door is open, a spring for maintaining said detent in holding engagement with said stop member to hold the door open. 70 75

- when said spring is under tension, a lever having one end fulcrumed on said arm adapted to be swung toward and from said arm, and provided with an abutment for holding said spring under tension when the lever is held in one position, a latching device for holding the lever in said position, and an electro-magnetically operated means acting when energized to release said latching device from said lever.
6. The combination of a door, a door closer comprising a spring tending to close the door, and a holding device for holding the door open against the tension of said spring, a locking device for the door normally in unlocked condition, and controllable means comprising an elec-

tric circuit acting when the circuit is closed to release said holding means and to lock said locking device, and means acting automatically upon release of said holding means to open the circuit.

7. In a door closer, the combination of a spring actuated door closing arm, a stop member, a detent carried by said arm and adapted to engage said stop member when the door is open, a spring for maintaining said detent in holding engagement with said stop member to hold the door open when said spring is under tension, a device for holding said spring under tension, and an electro-magnetically operated means acting when energized to release said holding device.

WALLACE F. MOORE. 15
